CHARLES H. ROLLASON, OF WHEELING, WEST VIRGINIA, ASSIGNOR TO WHEELING STEEL CORPORATION, OF WHEELING, WEST VIRGINIA, A CORPORATION OF DELAWARE

APPARATUS FOR HEADING SHEET METAL CONTAINERS

Application filed October 15, 1930. Serial No. 483,930.

This invention relates broadly to apparatus for heading sheet metal containers; and it has for its primary object to provide a mechanism for effecting the heading of sheet metal barrels, drums and like containers in an efficient and expeditious manner and without crushing or deforming any part of the container.

A further object is to provide, in association with mechanism for seaming heads on barrel bodies, means for rigidly supporting the head ends of such bodies during the seaming of heads thereon.

With these and other objects in view, the invention resides in the features of construction, arrangement of parts and combinations of elements which will hereinafter be fully described, reference being had to the accompanying drawings, in which—

20 Figure 1 is a side elevation of the invention, parts thereof being shown broken;

Figure 2 is a top plan view of the mechanism for supporting the head end of the container during the heading operation;

25 Figure 3 is a detail section of the head end of a container with the head loosely mounted therein, illustrating the application of the means for supporting said end during the head attaching operation; and—

30 Figure 4 is a similar view showing the parts as they appear at the conclusion of the head attaching operation.

Referring to said drawings, 1 designates a stationary upright column upon which is rigidly carried a supporting frame or yoke 2 embodying substantially parallel horizontally directed arm-like members 3 and 4 having on their respective ends sleeve-bearings 5 and 6 disposed in vertically alined relation. Said bearings have journaled for rotation therein a vertical spindle 7 upon the lower end of which is mounted a chuck 8 which carries on its under side a plurality of seaming rollers 9. In order to provide for vertical reciprocation of said chuck 8 relative to the work, said spindle 7 is made longitudinally shiftable in its said bearings.

Fixed on the spindle in suitable locations between the bearings 5 and 6 are two relatively spaced collars 10 and 11, and interposed

in embracing relation to said spindle between said collars is a shifter ring 12 having said spindle rotatable relative thereto. Said shifter ring has pivotally attached to diametrically opposite sides thereof the upper 55 ends of two parallel links 13 which have their lower ends rigidly mounted on the opposite ends of a transversely disposed horizontal shaft 14 which is mounted for rotary movement in or on the lower member or arm 60 4 of the yoke 2. Said links 13, which normally function to support the spindle 7 and the thereby-carried chuck 8 in elevated position, are jointed intermediate their ends, each being formed of two pivotally connected 65 members which normally occupy alined relation. The joint 15 of each link is of knuckle type, permitting breaking, or relative angular movement, of said link members in a forward direction only from their relatively 70 alined positions, such breaking being intended to permit said spindle to drop for lowering the chuck upon the work. A retractile coil spring 16 connected at one end to one of the members of each link adjacent to said joint 15 75 and at its opposite end to a fixed part, as to a bracket 17 stationarily mounted at an appropriately elevated point on the yoke, normally maintains the members of each link 80 in their alined relation.

A hand lever 18 fixed on one end of the shaft 14 is provided whereby the latter may be rotated forwardly to effect the breaking of the joints 15 of the links as required to permit the spindle and the chuck to descend for 85 disposing the seaming rollers 9 in operative relation to the work.

The spindle 7 is rotated in any suitable manner, as through gearing connecting it with an appropriately located power transmission shaft. As herein shown, said transmission shaft carries a bevel gear 20 in driving relation to a similar gear 21 fixed on a vertical shaft 22 journaled in bearings, as 90 23 and 24, the latter formed on the yoke 2. 95 A bevel gear 25 fixed on the upper end portion of said shaft 22 is disposed in driving relation to a similar gear 26 fixed on one end of a horizontal shaft 27 journaled in bearings 28 mounted on the arm 3 of the yoke. The op- 100

posite end of said shaft 27 carries a bevel gear 29 occupying driving relation to a similar gear 30 which rests upon the top of said arm 3 and which is splined on the spindle and relative to which the latter is vertically shiftable.

Vertically adjustable relative to the yoke 2, as along the column 1 and the upright shaft 22, is a supporting member 31 having a forwardly projecting arm 32. Said member is supported by and is adjusted vertically by means of a screw 33. Said screw, which has its upper end swiveled at 34 on the under side of the yoke 2, has threaded engagement with 15 said member 31. Thus, adjustment to position said member at a greater or less elevation is effected by rotating said screw in the required direction.

The arm 32 of the supporting member 31 20 constitutes a mounting upon which is rigidly carried one member or section 35 of a horizontally disposed two-section clamping ring designed to embrace a sheet-metal drum body during the operation of seaming a head thereon by means of the rollers 9 of the chuck 8. Said ring section 35, which is substantially semi-circular in form, is further supported by appropriately located legs 36, and pivotally attached to one end of said section is an end 25 of a complementary section 37 which is supported by one or more legs 38 having rollers or casters 39 for travel on the floor during opening and closing movements of said section relative to the stationary section 35.

35 The opposite ends of said clamping ring sections 35 and 37 are provided with means whereby they may temporarily be rigidly connected for rigidly holding within their embrace the bodies of drums 40 during the operation of seaming heads thereon. Said means, as herein shown, comprises a projecting hook 41 rigidly carried by the end of the section 37 and a part 42 interengageable therewith, said part 42 being borne by a lever-like handle 43 40 which is pivotally mounted on the corresponding end of the ring section 35. Said handle is adapted to be swung manually to and from a position wherein the part 42 interengages the hook 41 for holding said ring sections in fixed relation, maintaining the embraced drum body in stationary position directly under and in properly aligned or centered relation to the chuck 8.

50 A handle 44 fixed on the ring section 37 in a suitable position serves as means whereby said section may be swung to and from its open position with respect to the stationary section 35 for permitting introduction and removal of drums relative to said sections.

55 Said clamping ring is designed to seat within an annular channel 45 formed exteriorly of the drum by the provision in the latter of an internal annular bead 46. The upper surface of said bead constitutes a seating ledge or shoulder for the head 47 which

is to be seamed on the drum body 40. During the seaming operation, in which the seaming rollers 9 of the then lowered chuck 8 act forcibly upon the end flange 48 of said drum body and the annular flange 49 of the head 70 47 to form the roll-like seam 50, the inner edge portion of said clamping ring closely underlies said bead-formed ledge or shoulder and is adapted to sustain the downwardly directed seaming pressure or force exerted by 75 the rollers 9, thus relieving the bead and the underlying portion of the drum body from the distorting or metal-buckling strains which would otherwise be imposed thereon.

The upper face of the clamping ring has 80 formed therein adjacent to its inner edge a shallow channel 51, arcuate in cross section, into which, in the heading operation, the metal of the seating ledge or shoulder is 85 forced and with the curvature of which said ledge is caused to conform, as shown in Fig. 4.

What is claimed is—

1. In drum heading apparatus, the combination with a chuck carrying seaming rollers, and means for shifting said chuck to carry said rollers into and out of operative seaming relation to the end of a drum body and a head mounted on the latter, of a sectional ring for embracing said drum body in underlying supporting relation to an offset shoulder formed in its said end, and means rigidly supporting said ring, said ring being adapted to relieve the body below said shoulder of roller-imposed pressure strains and having in its top face a channel into which said shoulder is depressible. 90

95 2. In drum heading apparatus, the combination with a chuck carrying seaming rollers, and means for shifting said chuck to carry said rollers into and out of operative seaming relation to the end of a drum body and a head mounted on the latter, of a sectional ring for embracing said drum body in underlying supporting relation to an offset shoulder formed in its said end, one section of said ring being stationarily supported and having an end of a companion section pivotally mounted on an end thereof, means for connecting the opposite ends of said sections in rigid relation, and legs supporting said companion section. 100

105 3. In apparatus for seaming heads on sheet metal drum bodies, a chuck, seaming rollers carried by said chuck, means for moving said chuck to and from a position presenting said rollers in operative relation to the drum body and the head, said means including jointed links normally occupying positions maintaining said chuck in elevated position and breakable at their joints to permit lowering of said chuck, means for rotating said chuck, a sectional clamping ring for embracing said body adjacent to the end to be headed and adapted to support 110 115 120 125 130

said end during the seaming operation, preventing the imposition of strains on the drum body below said ring.

4. In apparatus for seaming heads on sheet metal drum bodies, a chuck, seaming rollers carried by said chuck, means for moving said chuck to and from a position presenting said rollers in operative relation to the drum body and the head, means for rotating said chuck, a sectional clamping ring for embracing said body in underlying relation to a head-seating shoulder provided in the latter, said ring being adapted to support said shoulder during the operation of said seaming rollers, one section of said ring being stationarily supported and a companion section thereof having pivotal connection at one end with said stationary section and being shiftable on said connection to and from complementary relation to the latter.

In testimony whereof, I affix my signature.

CHARLES H. ROLLASON.
